(57) **CLAIM**

The ornamental design for a roller chain outer plate link as shown and described.

DESCRIPTION

FIG. 1 is a front perspective view of a roller chain outer plate link.

FIG. 2 is a rear perspective view of the roller chain outer plate link in FIG. 1.

FIG. 3 is a front view of the roller chain outer plate link in FIG. 1.

FIG. 4 is a rear view of the roller chain outer plate link in FIG. 1.

FIG. 5 is a right end view of the roller chain outer plate link in FIG. 1.

FIG. 6 is a left end view of the roller chain outer plate link in FIG. 1.

FIG. 7 is a top view of the roller chain outer plate link in FIG. 1; and,

FIG. 8 is a bottom view of the roller chain outer plate link in FIG. 1.

The broken lines in the figures are for the purpose of illustrating portions of the roller chain outer plate link and form no part of the claimed design. The roller chain outer plate link is shown with symbolic breaks in its length, shown in dash-dot broken lines. The appearance of any portion of the article between the break lines, including the dash-dot broken lines, forms no part of the claimed design.
